TAKE-UP MECHANISM FOR TEXTILE MACHINES

Herman L. Weisler, Petersburg, and John H. Pope,
Hopewell, Va., assignors to Tubize Chatillon
Corporation, a corporation of Delaware

Application September 4, 1941, Serial No. 409,482

4 Claims. (Cl. 66—149)

This invention relates to textile machines and particularly to the fabric take-up device of such machines. The invention aims to provide certain improvements in the driving mechanism for the take-up roll of textile machines.

The fabric produced on textile machines is commonly wound, as produced, on a take-up roll. Various devices are employed for driving the take-up roll at a speed correlated to the speed of production of the fabric. For example, the take-up roll in certain tricot knitting machines is operatively connected to a worm gear and cooperating driving worm. A reciprocable element, embodied in the machine, imparts on its forward movement an intermittent driving stroke to the worm by means of a clutch designed to permit backward movement of the reciprocable element without moving the worm. Our actual experience with such machines has demonstrated that after a comparatively short period of use the clutch face becomes slightly grooved by the clutch rollers so that these parts require constant polishing and attention, and since the condition becomes progressively worse, these parts have to be frequently replaced.

Our present invention aims particularly to provide an improved drive for the take-up roll of such tricot knitting machines, although the invention may be used with advantage for driving the fabric take-up roll of various other types of textile machines. In accordance with the invention the take-up roll is operatively connected to a worm and worm gear, and an intermittent driving stroke is imparted to the worm by fixing the worm on a rotatable shaft adapted to be rotated in only one direction by a pawl and ratchet operatively associated with a reciprocable slide bar embodied in the machine. These and other novel features of the invention will be best understood from the following description taken in conjunction with the accompanying drawing in which:

Fig. 1 is a perspective view of the improved take-up roll drive of the invention, and

Fig. 2 is a side elevation thereof.

The take-up mechanism of the tricot knitting machine, to which the invention is shown applied in the drawing, is operated by an actuating lever 5 contacting an eccentric cam 6 at its lower end and operatively engaging a reciprocable slide bar 7 at its upper end. As will be well understood by those skilled in the art, the oscillating lever 5 imparts an intermittent driving stroke to the reciprocable slide bar 7. A spring 8 directly connected to the slide bar returns the latter to its

initial position after each driving stroke. The entire take-up assembly is free-swinging, changing its angle as the amount of fabric on the take-up roll increases, and includes means for regulating the travel of the slide bar to compensate for the gradual increase in diameter of the roll of fabric, but as these features constitute no part of our invention they are not shown on the drawing.

10 The fabric 9 being produced on the machine is wound on a take-up roll fixed on a rotatably mounted shaft 10. A comparatively wide ratchet 11 is also fixed to the shaft 10. A series of staggered pawls 12 cooperate with the ratchet 11 to prevent backsliding of the take-up roll and fabric thereon within a fraction of the distance of one ratchet tooth.

The shaft 10 is adapted to be driven forwardly, that is to wind the fabric 9 on the take-up roll, by a worm-gear 13 operatively connected thereto. 20 A worm 14 fixed on a rotatable shaft 15 meshes with the worm-gear 13. The worm 14 and worm-gear 13 are preferably of the self-locking type so that the worm-gear 13 can rotate in only one direction. A ratchet 16 is fixed on the shaft 15. The slide bar 7 carries a pawl 17 which is pressed by a spring 18 in operative engagement with the teeth of the ratchet. As a safety measure, in the event the self-locking worm and worm-gear should fail to operate, a worm holding ratchet 19 (fixed on the shaft 15) and cooperating pawls 20 are provided to assure movement of the worm in only the forward direction.

25 In the operation of the take-up mechanism embodying the invention, the pawl 17 on the reciprocating slide bar 7 imparts an intermittent driving stroke to the ratchet 16. The spring 8 returns the slide bar to its initial position after each driving stroke, the pawl 17 slipping freely over the ratchet teeth during the backward movements of the slide bar. With each driving stroke of the ratchet 16, the worm 14 imparts a corresponding driving stroke to the worm gear 13 and hence to the fabric take-up roll. Backsliding 30 of the worm is prevented by its self-locking engagement with the worm gear, and is additionally prevented by the ratchet and pawls 19—20. In case the worm and worm gear are not of the self-locking type, the ratchet and pawls 19—20 are necessary and not optional.

35 The invention provides a simple, effective, long-wearing and inexpensive drive for the take-up roll. Contrasted with the heretofore customary drive for a tricot knitting machine, it reduces the number of parts of the worm and its cooper-

ating clutch from eleven to one or two at the most; the worm 14 and shaft 15 in the drive of the invention being a conventional type of single piece construction. However, the worm 14 and shaft 15 may be made in two pieces keyed together, where such construction is desirable. The only parts subject to wear in the drive of the invention are the comparatively large ratchet 16 and cooperating pawl 17, and experience has demonstrated that infrequent replacement of these parts is required. Moreover, the drive of the invention is relatively inexpensive and requires no special skill in making and assembling, whereas the hereinbefore mentioned clutch drive is costly to produce, and requires the services of skilled toolmakers.

We claim:

1. In a textile machine having a take-up roll for fabric produced thereon, the combination with a worm gear operatively connected to said take-up roll, of a worm meshing with said worm gear, a rotatable shaft on which said worm is fixed, a ratchet fixed on said shaft, a reciprocable slide bar having a pawl cooperating with said ratchet, means for intermittently moving said slide bar in the direction to cause said pawl to impart a predetermined driving stroke to said ratchet, and means for returning said slide bar to its initial position after each driving stroke.

2. In a textile machine having a take-up roll for fabric produced thereon, the combination with a worm gear operatively connected to said take-up roll, of a worm meshing with said worm gear, a rotatably mounted shaft on which said worm is fixed, a ratchet fixed on said shaft, a reciprocable slide bar having a pawl cooperating with said ratchet, means for intermittently moving

said slide bar in the direction to cause said pawl to impart a predetermined driving stroke to said ratchet, a spring for returning said slide bar to its initial position after each driving stroke, and a second ratchet fixed to said shaft and a pawl cooperating therewith for preventing backward movement of said worm during the return movement of said slide bar.

3. In a textile machine having a take-up roll for fabric produced thereon, the combination with a worm gear operatively connected to said take-up roll and a pawl and ratchet for preventing backsiding of the roll, of a worm meshing with said worm gear, a rotatable shaft on which said worm is fixed, a ratchet fixed on said shaft, a reciprocable slide bar carrying a pawl cooperating with said ratchet, means for intermittently moving said slide bar in the direction to cause said pawl to impart a predetermined driving stroke to said ratchet, and a spring for returning said slide bar to its initial position after each driving stroke.

4. In a tricot knitting machine having a take-up roll for fabric produced thereon, the combination with a self-locking type of worm and worm gear operatively connected to said take-up roll, of a ratchet, a rotatably mounted shaft on which said worm and ratchet are fixed, a reciprocable slide bar having a spring-pressed pawl operatively engaging said ratchet, and means embodied in said machine for intermittently moving said slide bar in the direction to cause said pawl to impart a predetermined driving stroke to said ratchet, and a spring for returning said slide bar to its initial position after each driving stroke.
